United States Patent Office

Des. 214,937
Patented Aug. 12, 1969

214,937

WATCH BRACELET OR SIMILAR ARTICLE

Ananta Uengsakul, Bangkok, Thailand, assignor to Stelux Manufacturing Company, Ltd., Kowloon, Hong Kong, a corporation of Hong Kong

Filed July 3, 1968, Ser. No. 12,615

Term of patent 14 years

Int. Cl. D11—01

U.S. Cl. D45—4

The dominant features of my new design reside in the portions shown in full lines.

I claim:

The ornamental design for a watch bracelet or similar article, substantially as shown and described.
